UNITED STATES PATENT OFFICE

MANFRED SCHLEICHER, OF BERLIN-CHARLOTTENBURG, AND LEO BRANDENBURGER, OF BERLIN-HALENSEE, GERMANY, ASSIGNORS TO SIEMENS & HALSKE AKTIEN-GESELLSCHAFT, OF SIEMENSSTADT, NEAR BERLIN, GERMANY, A CORPORATION OF GERMANY

MEANS FOR INDICATING THE POSITION OF A CONNECTER SWITCH

Application filed November 18, 1927, Serial No. 233,545, and in Germany March 22, 1927.

It is customary to operate the oil switches of a central station, or of a substation not directly but by remote control, partly because the attendant has to remain out of range of the high voltage obtaining in the circuit, or because distributed switch devices have to be operated from a single control room. In order to make possible reliable supervision of the switch devices, indicating devices are generally provided which indicate at the control point the position of the various switches and the like.

It may happen that the oil switch of a line in which there is a short circuit, will be closed from the control room. The excessive current relay or some other line protection relay provided for the purpose, may then become operative and open the oil switch before the indicator device had time to indicate its final position in the control room. In such cases the only thing that can be seen in the control room is that the oil switch failed to obey the switching in operation. Repetitions of the above operation are liable to lead to a dangerous overheating of the oil switch and of other important parts. In order to avoid this, drops or flaps which are released directly by the line protection relays could be arranged in the control room. In the case of large installations, this means however a large number of signalling devices and signal wires—a drawback which is remedied by the present invention.

The invention starts with the idea that the operation of a line protection relay is a sure sign that the oil switch was closed, if not completely, at least to such an extent that the corresponding faulty line received energy. For that reason, according to the invention the device indicating the position of the line switch which may be released by a line protection relay, can be operated not only by the same but also by the line protection relay. This makes it certain that the notification of the switching in process and of the automatic

switching off reaches the control room without it being necessary to provide separate indicator devices and signal wires. The invention is of special importance for remote control installations in which the oil switches have to be operated from a great distance by means of a limited number of control and return notification lines.

In the accompanying drawings Figs. 1 and 2 are diagrams illustrating examples of the invention.

In the diagrammatic illustrations switch devices arranged in a secondary room N, are to be operated from a main point or room H, said rooms being connected together by distance lines 13 and 14. The line 13 connects together the centres of rotation of two contact arms 15, 16 which travel over contact discs 17 and 18 in such a manner that they successively touch simultaneously, two contacts corresponding to each other. To that end any desired devices are provided which ensure synchronous movement of the two arms, and which need not be more fully described here.

Of the switch devices arranged in the secondary room N, there is shown here by way of example merely the control device for an oil switch, to the spindle 1 of which is keyed the armature-lever 2. When the oil switch is to be operated, a control switch 19 in the main room H is moved against one of its two contacts 20 and 21. The control switch 19 is connected by a wire 22 to the contact 23 of the disc 17 which corresponds to the contact 24 on the disc 18. If the oil switch is to be switched in for instance, the contact lever 19 is set against the contact 20. A current will then pass from the positive pole of the source of current 25 through the wires 26 and 27, contact 20, control switch 19, wire 22, contact 23, contact arm 15, distant line 13, contact arm 16, contact 24 through the winding 29 of a polarized relay and the wires 30 and 14, back to the zero point of the source of cur-

rent 25. The winding 29 of the polarized relay will accordingly receive a positive current impulse; consequently the contact blade 8 of the said relay will be moved against its contact 31. The contact blade 8 is connected to the neutral or zero conductor 10 of a battery 9 through various windings which will be described further on. As soon as contact blade 8 touches the contact 31, an electromagnet 3 will receive a current impulse from the positive wire 11 of the battery and will pull the armature lever 2 in opposition to the action of the spring 4, into the position shown. As soon as the contact arms 15 and 16 have left the contacts 23 and 24, the contact blade 8 returns to its zero position, and current is cut off from the electromagnet 3. The armature lever 2 however remains in its adjusted position, as its projection 6 engages with a locking lever 5. If the oil switch is to be switched out again, the control switch 19 is moved into engagement with its second contact 21 which is connected by the wires 28 and 33 to the negative pole of the source of current 25. Under such conditions when the contact arms 15 and 16 again engage their contacts 23 and 24, the winding 29 of the polarized relay will receive a negative current impulse. The contact blade 8 will accordingly be shifted into engagement with the contact 32 from which a wire 34 leads to the electromagnet 7, and the latter will be energized and will pull the locking pawl 5 out of its locking position, and thus permit the spring 4 to pull the armature lever 2 back into the switched out position.

To the armature lever 2 a switch 35 is connected by a rod 63, so that when the armature lever 2 is in the switching in position, the switch lever 35 will engage with its contact 36, and when in the switching out position, with a second contact 37. In the switching in position shown in the drawing, the positive pole of the source of current 9 is connected through the wires 11 and 38, contact 36, switch lever 35 and the wire 39, to one contact 41 of the contact disc 18, which contact 41 corresponds to the contact 40 of the contact disc 17. As soon as the two contact arms have reached these contacts, a connection will be established through the two contact arms and the distant line 13, with a polarized relay 42 which controls an indicator device 43, arranged to indicate to the attendant whether the oil switch in the secondary room is in the switched in or out position. The circuit passing through the polarized relay 42 is completed through the wire 64 and the distant line 14. If, contrary to what is shown in the drawing, the oil switch is not in the switched in, but in the switched out position, the switch 35, as indicated by dotted lines in the drawing, will be in engagement with a contact 37 which is connected through a switch 44 and a contact 45 with the negative pole of the

source of current 9. The polarized relay 42 will thus receive a negative current impulse and will bring the indicator device 43 into the position which indicates the switched out position.

If the contact arms 15 and 16 do not rotate too slowly, the current impulses which are sent through the single contacts of this contact disc, are relatively short. It is however desirable for movements of relatively large extent such as the switching in of an oil switch, to have available a somewhat longer time. For that reason, the polarized relay 29 is further provided with a hold on coil 46, so that as soon as the contact blade 8 engages with the contact 31 or the contact 32, the zero point of the source of current 9 will be connected through the wires 10 and 30 to said hold on coil 46. From the latter the connection leads through the heating coil 47 of a bimetallic spring 48 and a switch 49 to the contact blade 8. The hold on coil 46 receives current, namely from the positive pole of the source of current when the contact blade 8 engages the contact 31, and from the negative pole of the source of current when it engages the contact 32. The hold on coil holds the contact blade in one or the other position until the bimetallic spring is heated by the heating action of the winding 47 to such an extent that it bends and opens the switch 49. Only then will the contact blade 8 return to the zero position, and the magnet 3, or the release magnet 7, become dead.

The heavy current line is indicated by one of its phases 50 which includes a switch 71 connected with and controlled by the armature lever 2. The current transformer 51 feeds the excessive current relay 52. As soon as excessive current appears in the line, for instance owing to a short circuit, the excessive current relay 52 will attract its armature 53 and close a contact 54 which is electrically connected to a magnet winding 55. From the latter, the wire 56 leads to the release magnet 7, so that the latter will under the above conditions be energized and will open the oil switch.

At the same time the magnet winding 55 will be excited and will indicate to the main room if the oil switch was switched on a short circuit, even though it was thrown out again by the excessive current relay so quickly that the switch 35 either had not reached the contact 36 at all, or moved away from it again before the two contact arms reached the corresponding contacts 40 and 41. The working of the device is as follows:

Assuming that the armature lever 2 is not in the position shown in the drawings, but in the switched out position, and the lever 35 is in the position shown by dotted lines, on the contact 37, with the indicator device 43 in the main room indicating the switched out position. Under such conditions if the con-

trol lever 19 is turned over, the switching in electromagnet 3 will receive current as soon as the contact arms reach the contacts 23 and 24, and will pull the armature lever 2 into the position shown. Let it be further assumed that at the same moment the excessive current relay 52 also becomes operative owing to a short circuit in the line 50, and operates the locking lever 5, so that the armature lever 2 will at once return to the switched out position as soon as current has been cut off again from the magnet 3. When the contact arms 15 and 16 reach the indicator contacts 40 and 41, the lever 35 will under such conditions be already in engagement with the contact 37. At this stage however this contact is not connected to the negative pole of the source of current 9, but to the positive pole; this is due to the fact that the magnet winding 55 has also received current through the contact 54 of the excessive current magnet 52 and has brought the switch 44 against the contact 57 which is connected to the positive pole. To the centre of rotation of the switch 44 is moreover connected a hold on coil 58 from which a wire leads to the switch 59 and through the heating coil 60 of a bimetallic spring 61, to the negative pole of the source of current 9. The hold on coil 58 keeps the switch 44 in adjusted position until the arms 15 and 16 have reached the indicator contacts 40 and 41. At that moment, the indicator device 43 receives through the contact 57 of the switch 44, a positive current impulse, that is to say that direction of current which brings the indicator device into the switch closing position. This will show in the main room, in a reliable manner, that the coil switch had switched in the line 50. As soon however as the bimetallic rod has become heated and bent to such an extent that it opens the switch 59, the current will be cut off from the hold on coil 58, and the switch 44 will return to its position of rest on the contact 45. At the next revolution of the contact arms 15 and 16, the indicator device 43 will therefore again receive a negative current impulse, so that an attendant in the main room will see that the oil switch was immediately released again. In order to prevent the hold on coil from holding the armature lever 2 too long by means of the electromagnet 3, it may be advisable to carry its hold on circuit through contacts 72 arranged to be closed by the contact lever 53 of the excessive current magnet 52, and to immediately open the hold on circuit in case of an excessive current.

Examples of the arrangement are shown in Figs. 1 and 2 of the drawings in which the contacts 72 are connected respectively with the hold on coil 46 and the wire 30 which leads to the zero or neutral conductor 10 connected with the battery 9.

In the construction illustrated, the change-over switch 44 is held fast for a given length

of time in the change-over position by a hold on coil 58. The time period during which the coil 58 is active must be calculated so that it shall be sufficient to operate the indicator device 43 in a reliable manner. Instead of employing a retardation device such as the above which works for a given period of time independently of the other processes, the switch 44 could also be left in the change-over position until the contact arms reach the indicator contacts 40 and 41. For instance, the switch 44 could be brought back to the position of rest shown in the drawings, by the indicator current impulse produced, or also mechanically, by the contact arms 16. In such case, as shown in Fig. 2, the contact 37 may be connected with a relay 70 which is also connected with the switch 44 and serves to return the latter to its normal position when the arms 15 and 16 engage the indicator contacts 40 and 41.

What we claim as our invention and desire to secure by Letters Patent is:—

1. In a system for indicating the open and closed positions of a switch, the combination of an electric circuit controlled by the switch, an indicating device, electromagnetic means for variably operating the indicating device, means controlled by the switch in accordance with the open and closed position thereof for controlling the operation of the operating means to cause the indicating device to indicate the then position of the switch, an overload relay associated with the electric circuit controlled by the switch, a switching means, means controlled by the overload relay for operating the switching means, means controlled by the switching means for rendering the indicating device operating means non-responsive to the switch controlled means and to operate the indicator operating means to cause the indicator to indicate incorrectly that the switch is closed, and retarded operating means for restoring the switching means controlled by the overload relay to normal position and thereby restore the indicating device operating means to the control of the switch operated means to indicate the then position of the switch.

2. In a system for indicating the open and closed positions of a switch, the combination of an electric circuit controlled by the switch, an indicating device responsive to changes in the direction of current, electromagnetic means for operating the indicating device to indicate the open and closed positions of said switch, an auxiliary switch controlled by said switch, an electric circuit for said electromagnetic means in which the current direction depends upon the position of said auxiliary switch, an overload relay for protecting the electric circuit controlled by the first switch, a switching means, means controlled by the overload relay for operating the switching means, means controlled by the overload relay for operating

switching means for rendering the indicating device operating means non-responsive to the means controlled by the first switch and to operate the indicator operating means to indicate incorrectly that the first switch is closed, and retarded operating means for restoring the switching means controlled by the overload relay to normal position and thereby restore the indicating device operating means to the control of the means for operating the first switch to indicate the then position of the first switch.

10 In testimony whereof we affix our signatures.
